CASING PERFORATING GUN

Ford I. Alexander, Whittier, Calif.

Application July 24, 1939, Serial No. 286,181

12 Claims. (Cl. 164—0.5)

This invention relates generally to perforating guns for well casing and more particularly to improvements in the shooting bores and explosion chambers of perforating guns.

The conventional perforating gun for well casing comprises a cylindrical body formed in its sides with a plurality of screw-threaded sockets, into which are screwed barrels provided with projectile shooting bores. An explosion chamber is formed in the body back of each barrel, into which is placed a powder charge, and the charge is fired by means of a firing element, typically set off by an electric current supplied from a cable extending downwardly through a duct in the gun body. A disadvantage in this conventional construction is that the barrel and shooting bore tend to be comparatively short, with resulting loss of firing power.

A general object of the present invention is to provide a novel perforating gun construction in which the shooting bore may conveniently be made of substantially increased length.

A further object of the invention is to provide a perforating gun design affording enhanced inherent structural strength in the part or parts in which the shooting bore and explosion chamber are formed.

A still further object of the invention is to provide an electrically fired perforating gun having an improved arrangement for the electric cable and an improved means for connecting the electric firing elements to the cable.

In one aspect of the invention, the shooting bore is formed in the gun body, instead of in an insert barrel, while the explosion chamber is formed in the inner end of a breech plug screwed within a socket sunk in the side of the gun body, or in the inner end of the socket between the breech plug and the breech end of the shooting bore. With this improved construction, the shooting bore becomes at once of increased length, extending from the bottom of the socket sunk in one side of the gun body to the muzzle which opens at the opposite side of the body. The bore being in the gun body proper, a stronger construction is afforded. To increase the life of the shooting bore, it may, if desired, be furnished with a replaceable liner. The plug houses, or forms an abutment in back of, the firing chamber and powder charge, and contains the firing element or fuse. The explosion chamber and shooting bore are located within a relatively thick mass of metal, and the breech plug affords a strong type of closure, so that an unusually sturdy construction is afforded.

In one form of the invention, the explosion chamber is contained within a cavity in the inner end of the breech plug. As will be evident, this novel type of breech plug is not necessarily limited to use in connection with a gun having a shooting bore in the main gun body.

The electric cable which ignites the fuses is preferably received within a spiral groove sunk in the outer surface of the body of the gun and which passes in turn the outer ends of the explosion chamber plugs mounted in the gun body. Electrical connections are made from this cable to the fuse in each explosion chamber plug through a suitably packed duct formed in the plug.

The invention will be more fully understood from the following detailed description of present preferred embodiments thereof, reference for this purpose being had to the accompanying drawing, in which:

Fig. 1 is a side elevation, with parts broken away, of a perforating gun in accordance with the invention;

Fig. 2 is a section taken on line 2—2 of Fig. 1; Fig. 2a is a view similar to Fig. 2, but showing a modified construction;

Fig. 3 is a section taken on line 3—3 of Fig. 1; and

Fig. 4 is a fragmentary view showing a modification.

Reference is now directed to the drawing, and particularly to Figs. 1, 2 and 3. In Fig. 2a, which shows certain modified structure, members corresponding to members in Fig. 2 are identified by the same numerals but with the letter *a* adjoined.

The cylindrical gun body is designated generally at 10, said body being shown as provided at the top with a screw-threaded pin 11 adapted for connection with a sub or other means, not illustrated, but which will be understood to be adapted for connection with the lowering line. Body 10 is provided with a plurality of horizontal, radially disposed shooting bores 12, spaced from one another longitudinally of and around the gun body. In the specific embodiment illustrated in Fig. 1, the shooting bores are spaced around the gun body by an interval of 90°, and while this arrangement is preferred, and the present invention lends itself especially well to such an arrangement, this is of course not to be understood as limitative of the invention considered in its broader aspects. Sunk into the side of the gun body in axial alignment with each of bores 12 is a socket 13, the inner end of

which meets the inner end of bore 12, and is defined by an annular shoulder 14. Socket 13 is furnished with screw-threads 15 extending inwardly from its outer end to a point which is preferably and typically approximately two-thirds of its depth, as illustrated in the drawing, thus leaving a straight walled inner section at 16. Preferably, this straight walled section 16 tapers or converges somewhat toward shoulder 14, for a purpose later to be explained, and is so illustrated in Fig. 2, though in Fig. 2a the surface 16a joining the screw-threaded portion of socket 13a with shoulder 14a is not provided with such a taper, and in certain cases the construction of Fig. 2a may be satisfactory.

Screw-threaded within socket 13 is an explosion chamber plug or breech plug 20, the latter being externally screw-threaded as at 21 for engagement with threads 15, and having an inner end portion 22 adapted to seat against surface 16, with its inner end 23 terminating just short of annular shoulder 14. The outer surface 24 of this forward or inner end portion 22 of plug 20 is formed at the same angle as body surface 16, being therefore tapered complementarily to surface 16 in the instance of Fig. 2. In Fig. 2a, the plug 20a has an inner end portion 22a of cylindrical shape, which slidably engages the cylindrical surface 16a at the inner end of the socket.

Formed in the inner end of plug 20 is an explosion chamber 25, the depth of which is typically and preferably approximately one-third the length of plug 20. This chamber 25 is adapted to contain a powder charge 26. A frangible disk 27 is seated within a countersink 28 formed in the end of plug 20 and serves as a closure for the explosion chamber, sealing said chamber against external liquid pressure. A lead sealing ring 29 seated on annular seat 14 is engaged by the inner end 23 of plug 20 and by disk 27 when the plug is screwed home within socket 13. In the instance of Fig. 2, the inner end 23 of the plug is in tight, sealing engagement with sealing ring 29 on seat 14 by the time or just prior to the time its tapered surface 24 engages the tapered surface 16 of the socket. This provision assures a liquid tight seal for the explosion chamber, both the inner end 23 of the plug and the frangible disk 27 being pressed into sealing engagement with sealing ring 29.

A projectile is indicated at 30, positioned adjacent disk 27. The outer end or muzzle of bore 12 is preferably closed by a liquid seal 31.

Since plug 20 receives a considerable impact from the explosion within chamber 25, its screw-threaded connection with body 10 must be adequate to withstand the stresses existing at such time. In the form of Fig. 2, a conventional V-thread is employed, of a pitch of eight threads to the inch. In Fig. 2a, a buttress thread is employed, as illustrated. Either type is deemed suitable, though of course any other appropriate threading or locking arrangement may be employed if desired.

In Fig. 2a, the shooting bore 12a is shown equipped with a replaceable liner 35, which is screw-threaded in position by means of threads such as indicated at 36. It will of course be understood that such a liner may be employed in the form of Figs. 1 and 2 if desired.

An electrical fuse 37 is positioned in plug 20 in a bore 38 opening to firing chamber 25, the inner end of said fuse being immediately adjacent powder charge 26. An electrical conductor 39

connected to fuse 37 extends through a duct 40 and enlarged packing gland bore 41 out through the outer end of the plug. This conductor 39 is preferably an enamel insulated copper wire. The packing gland for said wire consists of a packing ring 42, composed for example of rubber or the like, and a bushing 43 screwed within the outer portion of bore 41, the bushing compressing ring 42 tightly around wire 39 and thereby effectively sealing against liquid. In the form of the invention illustrated in the drawing, fuse 37 is provided with a single electrical connection 39, and it will be understood that the outside shell of the fuse will in such case be electrically grounded to plug 20, the electrical circuit extending from conductor 39 through the fuse to its grounded external shell. The construction of the fuse and its ground may be conventional and no detailed explanation will be necessary. Of course, in any case in which it may not be desired to ground one side of the fuse to the gun body, it will be necessary to bring two conductors out from the fuse, both of which must be packed against fluid. Because of the greater ease of packing a single wire, however, the single wire arrangement is ordinarily preferred.

Fig. 4 shows a modification in which the powder charge is positioned within the socket between the breech plug and shooting bore, but not actually within the end portion of the plug. In this figure, in which members corresponding to members in Fig. 1 are identified by the same reference numerals but with the sub-letter b annexed, the powder charge 26b is positioned within a reduced inner portion 60 of socket 13b immediately adjacent frangible disk 27b. The inner end of plug 20b is positioned adjacent the powder charge, which may be in the form of a pellet, and has a shoulder 61 that engages a sealing disk 62 and compresses it against an annular shoulder 63 formed at the inner end of the portion 60 of socket 13b. This sealing disk, which may be composed of lead, effects a seal against pressure fluid leaking past threads 15b. The provisions for the fuse 37b and its connecting lead may be substantially the same as in Fig. 1, and are so illustrated.

Various electrical systems for energizing the fuses 37, either successively or simultaneously, may be employed. If the projectiles of the gun are to be fired successively, it is of course necessary that a separate conductor be run from a suitable switch or distributor to the fuse of each firing chamber, while if the projectiles are all to be fired simultaneously, the fuses may be connected either in series with or parallel across a single electric firing circuit, as is well understood. For simplicity, I have illustrated only the arrangement in which the projectiles are fired simultaneously by an electrical firing circuit across which the fuses are connected in parallel arrangement, though it will be understood that either of the other arrangements may be substituted if desired. Thus, the electrical conductor 39 brought out through the duct in each of plugs 20 is electrically connected to an electrical cable 46, which in in this illustrative case consists of a single electrical conductor, covered with suitable insulation 46a (see Fig. 3). This conductor extends downwardly through a duct 47 in pin 11, said duct opening through the side wall of the cylindrical gun body at a point just above the uppermost firing chamber socket 13, as indicated in Fig. 1. The electrical circuit above the upper end of the gun may of course be con-

ventional and is therefore not shown. This conductor 46 is then received by a groove 48 sunk in the outer surface of cylindrical body 10; in the present illustrative embodiment, this groove is spirally arranged about body 10 and passes or intersects each of the sockets 13 in turn, in the arrangement clearly illustrated in Fig. 1.

The outer end of each of plugs 29 is provided with a plurality of notches 49 adapted to receive the conductor 46 where it crosses over, the plurality of notches being provided so that regardless of the position in which the plug may come to rest when screwed home in its socket, there will be a notch 49 in a convenient position for reception of the conductor 46. Connection is made between each fuse conductor 39 and conductor 46 by removing a portion of the insulation of conductor 46 and soldering conductor 39 thereto. The connection so made is then insulated in any suitable manner, as for instance by coating with shellac.

It will be understood that when conductor 46 is connected to a source of electrical current, the other side of which is grounded to gun body 10, electrical current will flow through each of fuses 37, thereby discharging powder charges 26 to expel the projectiles 30 from gun bores 12.

Attention is directed to the relatively long gun bore 12 resulting from the novel construction in accordance with the invention. This long bore results in sustaining the pressure back of the projectile for a longer period of time before the projectile is expelled, with the result that higher projectile velocity and higher penetrating power are obtained. Attention is further directed to the fact that the explosion chamber and firing bore are located within a relatively thick mass of metal, and that the breech plug releasably held within that mass is in itself of considerable mass and completes the enclosure of the explosion chamber, except at the discharge side thereof. At the same time, the area of the breech plug subjected to endwise pressure as the gun is fired is relatively small, so that the reactive force on the breech plug tending to drive it from its socket as the gun is fired is minimized. Thus it will be seen that an unusually sturdy construction is afforded, such as will prevent any tendency to rupture of the parts as firing occurs. The tapered seat 16 for the tapered forward end portion of the explosion chamber or breech plug assures easy removability of the plug after firing. The explosion within the explosion chambers sometimes tends to expand the forward end portion of the plug somewhat, and without this provision, a certain binding may result making removal of the plug somewhat difficult. The tapered construction of Fig. 2 avoids this difficulty, since the initial rotation of the plug results immediately in separating the tapered surfaces 16 and 24, following which the plug may be readily unscrewed from the socket.

It will be understood that the drawings and description are to be considered illustrative of and not restrictive on the broader claims appended hereto, since various changes in design, structure and arrangement may be made without departing from the spirit and scope of the invention or of the appended claims.

I claim:

1. A casing perforating gun comprising a gun body, a socket formed in a side of said gun body, a shooting bore in said gun body extending from the inner end of said socket through said gun body, and an explosion chamber plug mounted

in said socket, said plug having an explosion chamber opening to the inner end of said shooting bore.

2. A casing perforating gun comprising a gun body, a screw-threaded socket formed in a side of said gun body, a shooting bore extending from the inner end of said socket through said gun body, and an explosion chamber plug screw-threaded within said socket, said plug having an explosion chamber opening to the inner end of said shooting bore.

3. A casing perforating gun comprising a gun body, a screw-threaded socket formed in a side of said gun body, said socket terminating in an annular seating surface, a shooting bore extending from said annular seating surface through the gun body, an explosion chamber plug screw-threaded within said socket, and a sealing ring mounted on said seating surface and adapted to be engaged by the inner end of said plug, said plug having an explosion chamber opening to the inner end of said shooting bore.

4. A casing perforating gun comprising a gun body, a screw-threaded socket formed in a side of said gun body, said socket terminating in an annular seating surface, a shooting bore extending from said annular seating surface through the gun body, an explosion chamber plug screw-threaded within said socket, said plug having an explosion chamber extending inwardly from its inner end, a frangible disk mounted adjacent the inner end of said plug and closing said explosion chamber, and a sealing ring seated on said annular seating surface and adapted to be engaged by said frangible disk at the inner end of the explosion chamber plug when said plug is screwed home in said socket.

5. A casing perforating gun comprising a gun body, a screw-threaded socket formed in a side of said gun body, said socket terminating in an annular seating surface, a shooting bore extending from said annular seating surface through the gun body, an explosion chamber plug screw-threaded within said socket, said plug having an explosion chamber extending inwardly from its inner end, a counter-sink in the end of said plug around said explosion chamber, a frangible disk mounted in said countersink with its outer surface flush with the end of the plug, and a sealing ring on said annular seating surface adapted to be engaged by the inner end of the explosion chamber plug and by said frangible disk when said plug is screwed home in said socket.

6. A casing perforating gun comprising a gun body, a socket formed in a side of said gun body, said socket having an outer screw-thread section and an inner inwardly tapering surface, a shooting bore extending from the inner end of said socket through said gun body, and an explosion chamber plug having an outer screw-threaded section adapted for screw-threaded engagement with the screw-threaded section of said socket and an inner section having a taper complementary to and adapted to seat on the tapered inner surface of said socket, said plug having an explosion chamber opening to the inner end of said shooting bore.

7. A casing perforating gun comprising a gun body, a socket formed in a side of said gun body, said socket having an outer screw-thread section and an inner inwardly tapering surface, said inwardly tapering section terminating in an annular seating surface, a shooting bore extending from said annular seating surface through the gun body, an explosion chamber plug having an

outer screw-threaded section adapted for screw-threaded engagement with the screw-threaded section of said socket and an inner section having a taper complementary to and adapted to seat on the tapered inner surface of said socket, said plug having an explosion chamber opening to the inner end of said shooting bore, and a sealing ring on said seating surface engaged and compressed by the inner end of said plug immediately prior to engagement between the tapered section of the plug with the tapered seating surface in the socket.

8. A casing perforating gun comprising a gun body, a screw-threaded socket formed in a side of said gun body, a shooting bore extending from the inner end of said socket through said gun body, an explosion chamber plug screw-threaded within said socket, said plug having an explosion chamber opening to the inner end of said shooting bore, and having a duct extending from said explosion chamber through the outer end of the plug, said duct being adapted to receive an electric fuse in a position adjacent said firing chamber, and to pass an electrical conductor attached to said fuse, and a packing gland for packing said conductor within said duct.

9. A casing perforating gun comprising an elongated gun body, a plurality of sockets sunk in the side of said gun body, said sockets being spaced from one another longitudinally of the gun body and being progressively spaced from one another around the gun body, a shooting bore extending from each of said sockets transversely through the gun body, a groove formed in the surface of the gun body extending around and lengthwise of the gun body so as to pass by the outer ends of said sockets in turn, an electrical cable received in said groove, explosion chamber plugs screw-threaded in said sockets, electrical

fuses mounted in said plugs adjacent said explosion chambers, and electrical connections extending from said fuses outwardly through the outer ends of said plugs and electrically connected to said cable.

10. A casing perforating gun comprising a gun body, a socket formed in a side of said gun body, a shooting bore in said gun body extending from the inner end of said socket through said gun body, and a plug mounted in said socket, there being an explosion chamber within said socket between the inner end of said plug and the inner end of said shooting bore.

11. A casing perforating gun comprising a gun body, a socket formed in a side of said gun body, a shooting bore in said gun body extending from the inner end of said socket through said gun body, and a plug mounted in said socket, the inner end of said plug and the socket inwardly of said plug forming an explosion chamber.

12. In a casing perforating gun, a body having an exterior surface and having a breech plug socket extending inwardly from said surface, a shooting bore of lesser cross-sectional area than said socket aligned with said socket and extending from the inner end of said socket through said body and opening through an opposite exterior surface on said body, said socket and shooting bore extending straight through said body from one of said exterior surfaces to the other, and a breech plug removably mounted in said socket in axial alignment with said shooting bore and removable from said socket in a direction rearwardly from said shooting bore, said breech plug having in its inner end portion an interior explosion chamber cavity opening to the breech end of the shooting bore and adapted to contain an explosive charge.
